(57) **CLAIM**

The ornamental design for an axe head, as shown and described.

DESCRIPTION

FIG. 1 is a front perspective view of an axe head showing my new design;

FIG. 2 is right side elevation view thereof;

FIG. 3 is left side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a front perspective view, showing the claimed design in use.

The broken line showings of an axe handle in FIGS. 1-8 and halligans in FIG. 8 are for the purpose of illustrating the environment in which the design is associated and form no part of the claimed design.
